(57) **CLAIM**

I claim the ornamental design for a snap-off cutting device, as shown and described.

DESCRIPTION

FIG. 1 is a front, left side perspective view of the snap-off cutting device.

FIG. 2 is a front view of the snap-off cutting device.

FIG. 3 is a rear view of the snap-off cutting device.

FIG. 4 is a top view of the snap-off cutting device.

FIG. 5 is a bottom view of the snap-off cutting device.

FIG. 6 is a right side view of the snap-off cutting device.

FIG. 7 is a left side view of the snap-off cutting device.

FIG. 8 is a front, left side perspective view of the snap-off cutting device in an extended position.

FIG. 9 is a front, left side perspective view of the snap-off cutting device with the end cap detached from the housing.

FIG. 10 is a cross-sectional view of the end cap of the snap-off cutting device taken vertically along the line shown in FIG. 12.

FIG. 11 is a front, left side perspective view of the end cap of the snap-off cutting device.

FIG. 12 is a rear, right side perspective view of the end cap of the snap-off cutting device.

FIG. 13 is a front view of the end cap of the snap-off cutting device; and,

FIG. 14 is a rear view of the end cap of the snap-off cutting device.

The oblique line shading appearing on exterior surfaces of the end cap is intended to indicate transparent material.

The broken lines depict portions of the snap-off cutting device in which the design is embodied that form no part of the claimed design.

1 Claim, 3 Drawing Sheets
